GAS FUELED COMBUSTION CHAMBER AND AIR INLET BAFFLE

Filed May 6, 1948

UNITED STATES PATENT OFFICE

2,642,127

GAS FUELED COMBUSTION CHAMBER AND
AIR INLET BAFFLECharles W. Sievert, Los Angeles, Calif., assignor
to Frederick W. Sievert, Los Angeles, Calif.

Application May 6, 1948, Serial No. 25,428

2 Claims. (Cl. 158—7)

1

This invention relates to a flash type gas burner wherein firing occurs simultaneously with mixing.

An object of this invention is to improve upon prior burner structures in regard to capacity for more quickly producing the amount of heat required for a given purpose, for example, to heat a steam boiler or other heater sufficiently to cause it to produce the desired horse power.

Another object of the invention is to provide burner means particularly adapted for use with heaters having downwardly opening combustion chambers.

A further object of the invention is to provide a burner having baffle means constructed to eliminate or decrease objectionable panting.

Still another object of the invention is to provide a burner having annular baffle means which effects highly efficient operation.

Other objects, advantages and features of invention will hereinafter appear.

Referring to the accompanying drawing, which illustrates a preferred embodiment of the invention,

Fig. 1 is a horizontal section on line 1—1 of Fig. 2.

Fig. 2 is a vertical midsection on line 2—2 of Fig. 1, except that some parts through which the plane of section passes are shown in elevation.

Fig. 3 is a partly sectional and partly elevational view of the burner head per se, the plane of the sectioned portion of the view being indicated by line 3—3 on Fig. 2.

Referring in detail to the drawing, the burner head 5 is shown mounted in a concentric relation to the circular skirt 6 of a boiler structure 7, said burner head being shown in substantially the same horizontal plane as the lower end of said skirt. Said boiler structure is shown supported by posts 8, the upper end portions of said posts being externally secured to said skirt by welds 9.

In order to provide around said burner head the desired air draft an annular member 10, the diameter of which extends horizontally, is supported for vertical adjustment together with an elongated base plate 11 shown integral therewith and supplemented by twin segmental plates 12 one attached to each side of said base plate so as to make up a circular, horizontal plate structure surrounding the lower end of said annular member 10. Said segmental plates 12 are shown detachably connected to said base plate 11 by means of short bolts 11b which pass through apertured ear plates 11c cast integral with the

2

inner edge portions of the upper face of said segmental plates 12, the lower ends of said bolts having nuts 11d screwed onto them.

The aforesaid circular plate structure is supported for vertical adjustment upon upstanding bolts 12a the upper end portions of which pass through apertures therein, said bolts carrying upper nuts 13 which cooperate with lower lock nuts 14 to adjust the base plate structure together with said annular member 10 at the desired height in relation to the lower end portion of the boiler skirt 6. This adjustment only slightly affects the upflow of primary air immediately around the burner head, but does have a pronounced effect upon the upflow of the secondary air supply between the peripheries of the plates 11 and 12 and the lower edge of the boiler skirt 6, enabling the operator so to adjust the burner as to supply thereto proper proportions of primary and secondary air, thus preventing the burner from "panting" or making a noise during its operation.

The aforesaid burner head 5 to which the invention as an article of manufacture principally pertains, comprises a hollow shell of an inverted frusto-conical shape, having its upper end closed by a horizontal top wall 16 and its downwardly converging side wall 17 terminating below as a cylindrical, externally screwthreaded nipple 18. Said burner head 5, at the juncture of the wall 16, which closes the top thereof, with the aforesaid side wall 17, is furnished with a multiplicity of gas outlet passages 19 issuing from the interior of the burner head adjacent to the periphery of the outer or upper surface of said wall 16. Said passages are so positioned, that, when the burner is in operation they direct a circularly fan-shaped sheet of flame out around the periphery of said burner head at an upward inclination. Alternating with said air passages 19, the burner head has a series of exterior air supply grooves 20 which are shown occupying about the upper third of the burner wall 17. Each of said grooves widens and deepens toward its upper end and has an inwardly directed upper end portion 20a where the groove joins the upper surface of the top wall 16 of the burner head, the grooved edge portion of the burner head being beveled in an arcuate manner. Therefore the grooves are positioned to conduct outside air to points within the row of gas outlets provided by said passages 19, so that each outlet is well supplied on all sides with oxygenizing air.

The aforesaid passages 19 open out in vertically extending areas 19a which, before the grooves 20 are machined out, form parts of a truly cylind-

drical band around the burner head. The inclination and diameter of each of said passages may be varied considerably and its mouth still kept within the area 19a within which the groove opens out. By thus varying said passages the burner head is adapted for use when supplied with different fuels and in conjunction with different sizes of combustion chambers. The aforesaid top wall 16 of the burner head 5 is castellated or furnished with a set of upstanding lugs 16a grouped around the center of said wall so as to afford a tool-hold whereby the burner head can be conveniently rotated by a suitable tool to screw it onto or unscrew it from a suitable gas supply fixture, for example, the L-fitting 21 of the horizontal gas supply pipe 22 of Fig. 2, where the delivery end portion of said pipe is shown supported subjacent to the aforesaid annular base plate structure by means of a strap iron hanger 23 bolted thereto. For the purpose of igniting the gas issuing from the burner head a pilot 28 is shown.

In Fig. 2 the burner is shown associated with the already mentioned boiler structure 1, this type of boiler having vertical fire tubes 25, the lower ends of which open downwardly through the horizontal boiler head or plate 26 which forms the top wall of the combustion chamber 21. It is to be understood, however, that the burner head 5 may be advantageously installed in many other situations, provided a suitable combustion chamber is afforded thereabove and that such combustion chamber is furnished with the aforementioned flow of primary and secondary air in the proper proportions, to maintain which proportional flow it is necessary that the area of the secondary air intake be adjustable.

In the operation of the burner unoxygenized gas flows from any suitable source of supply into the burner through the supply pipe 22, L 21 and the nipple 18. The gas then issues from the circumferential row of passages 19 through the top of the burner at an upward inclination. This issuing gas is immediately mixed with primary air flowing upwardly between the burner head 5 and the annular member 10. That portion of the air which encounters the conical face of the burner is partially deflected, giving to it additional pressure at its juncture with the issuing gas. Also, part of the primary air which is not deflected by reason of the grooves 20 between the mouths of the jet passages 19 flows upwardly between the emitting jet streams, subsequently to mingle with the issuing gas. As the products of combustion continue in their conical dispersion they contact secondary air flowing into the combustion chamber 21 between the periphery of the base plate structures 11 and 12 and the lower edge of the skirt 6 (see arrows under the edge of said skirt in Fig. 2). Said

secondary air further oxygenizes the combustibles, so as to facilitate complete combustion.

The bolts 12a which support the base plate structure, being vertically adjustable, enable the operator to vary the amount of space between the periphery of the base plate structure and aforesaid skirt 6, so as properly to regulate admission of the secondary air, thus eliminating "panting" and noise during operation of the burner.

I claim:

1. In combination with a heater having a circumferential wall defining a downwardly opening combustion chamber, means adapted to support said wall with its lower end above a supporting surface, a horizontal annular burner baffle means disposed adjacent and below the lower end of said wall, said baffle means having a central opening, a burner means rising through said central opening adjacent the sides thereof and forming with said central opening a primary annular air feed passage, said baffle means being of a diameter less than the interior diameter of the combustion chamber wall and having its peripheral edge closely adjacent thereto to provide an annular uninterrupted secondary air feed passage between the periphery of the baffle means and the lower end of the chamber wall so that the secondary air is caused to travel upwardly as it is fed into the combustion chamber, the diameter of the central opening relative to the diameter of the baffle means being of the order of at least 1 to 3, and means for adjustably supporting said baffle means concentrically of the wall of the combustion chamber whereby in all portions of adjustment the inflow of secondary air will have an upward component.

2. The subject matter of claim 1 wherein the baffle means is supported on adjustable means adapted to stand on said chamber supporting surface for selective adjustment of the baffle relative to the lower end of the combustion chamber wall.

CHARLES W. SIEVERT.
